UNITED STATES PATENT OFFICE

2,522,052

TOOTH PULP TESTER

James J. Logan and Robert B. Logan,
Strafford, Pa.

Application July 3, 1947, Serial No. 758,880

5 Claims. (Cl. 128—2.1)

1

This invention relates to tooth pulp testers and more particularly to electrical devices of this general character which are adapted to determine the condition of dental pulp by passing electrical current therethrough. In the use of such a device, electric current is applied to a tooth to be tested by means of an electrode adapted to engage the tooth. Although the enamel and dentine of the tooth offer substantial resistance to the passage of current, a certain amount of current penetrates the tooth structure to the pulp, which contains the nerve and blood vessels. Usually a patient will experience a sensation when the current is passed through a normal healthy tooth pulp but will experience no sensation if the pulp is non-vital. This has been relied upon in the past as an indication of the condition of the pulp being tested. However, this is not always a true and accurate test as it has been found that in some cases a sensation may be felt even though the pulp is in poor condition. Sometimes a sensation is felt due to stimulation of the tissues surrounding the tooth rather than the pulp.

Prior tooth pulp testing devices generally have operated on the "brute force" principle. The object of such devices has been simply to force enough current through the tooth pulp to cause the patient to feel a sharp sensation if the pulp is vital. The sensation produced by this method has been in the nature of a shock which is uncomfortable and sometimes painful to the patient. Moreover, such method involves the application of substantial voltage and is hazardous to the patient. Further still, such method cannot and does not distinguish between a sensation due to irritation of the pulp and that due to stimulation of the tissues surrounding the tooth, and therefore it is unreliable.

The principal object of the present invention is to provide a tooth pulp testing device which operates on a different principle than that of prior devices, and which overcomes the objections of such devices. The device of this invention is adapted to apply a low D. C. voltage to the tooth pulp sufficient only to produce a mild and unobjectionable sensation, the voltage being of insufficient magnitude to constitute a hazard to the patient. The device is further adapted to produce a measurable current, in response to the said voltage, in a circuit having no connection with the patient. The device is highly sensitive and it is able to distinguish between the passage of current through the tooth pulp and the passage of current through the tissues surrounding the

tooth. It therefore affords a reliable means for testing tooth pulp.

The invention may be fully understood from the following detailed description with reference to the embodiment illustrated in the accompanying drawing, wherein Fig. 1 comprises a diagrammatic illustration of the electrical circuit, and a sectional illustration of the electrode probe; and Fig. 2 is a fragmentary plan view taken along line 2—2 of Fig. 1.

Referring to the drawing, there is provided a source of D. C. voltage which may comprise a transformer 1 and a rectifier 2 arranged in well-known manner as illustrated. The output voltage of the conventional transformer and rectifier combination shown, is applied to a voltage divider 3 having adjustable contacts 4 and 5. A choke coil 6 is interposed between the voltage source and the voltage divider 3, and an associated filter condenser 7 is provided together with a switch 8 by which the condenser may be connected or disconnected as desired. The reason for this will be explained later.

A D. C. voltage is derived from the divider 3 by way of adjustable contact 4 and is applied to a potentiometer 9. A D. C. voltage is also derived by way of adjustable contact 5 and is applied to a second potentiometer 10. A positive voltage is derived from potentiometer 9 by way of its adjustable contact 11 and is applied to the anodes 12 and 13 of a double triode vacuum tube 14. It will be noted that the adjustable contact 11 is connected directly to the anode 13 by way of conductor 15, while said contact is connected to the anode 12 through an indicator 16 which may be a conventional microammeter. A shunting resistor 17 and an associated switch 18 are connected in shunt relation with the meter 16 to enable variation of the deflection thereof.

Referring particularly to the double triode tube 14, the common cathode heater 19 thereof may be energized from a low voltage winding 20 of the transformer 1. It is important that the cathodes of the two tube sections be operated at the same temperature and this is achieved by virtue of the common heater energized from a single source. It will be noted further that the grid 21 of the right-hand section of the tube is connected to the cathode 22 through conductor 23. It will be seen therefore, that the right-hand section of the tube has a certain established current flow therethrough, depending upon the voltage applied to the anode 13. The left-hand section of the tube serves as an amplifier and the right-hand section acts as a stabilizer, as here-

inafter described. The two cathodes 22 and 24 are connected together and are connected to the lower end of potentiometer 9 through the ground connections illustrated.

By means of the adjustable contact 5 on the voltage divider 3, a low D. C. voltage is established across the potentiometer 10. A low positive voltage is derived from potentiometer 10 by way of its adjustable contact 25 and is applied to the grid 26 of the left-hand section of the tube 14, through a patient's body and through the tooth pulp, by means of an electrode 27 and a probe device 28. The electrode 27 is adapted to be applied to some portion of the patient's body and this electrode is preferably in the form of an arm band so that it is adapted to be applied to an arm of the patient. The probe device 28 comprises a hollow casing 29 through which a conductor 30 extends. This conductor interconnects the grid 26 and a probe 31, and it is provided with a grounded metallic shield 32 which is only partially shown. The probe 31 is adapted to be applied to the surface of a tooth to be tested. Preferably, the wire 30 is connected to a metal tube 31a which is adapted to have the probe 31 inserted therein. The probe may be formed of wood and it may be dipped in a saline solution just before it is used. This makes it possible to discard the probe after a test and to use a new probe on the next patient. Moreover, the wooden probe feels better to the patient than does a metal probe.

During use of the device, the low positive voltage derived from potentiometer 10 is transmitted through the patient's body and the pulp of the tooth under test to the grid 26. This produces a flow of plate current in the left-hand section of tube 14, and the magnitude of this current is indicated by the microammeter 16. It should be noted that when the device is in use, there are two circuits in operation—the low voltage grid circuit extending from potentiometer 10 through the patient's body and the tooth pulp to the grid 26, and the relatively high voltage plate circuit extending from potentiometer 9 through the microammeter 16 to the plate 12. A current of relatively low magnitude flows in the first circuit through the tooth pulp and produces a mild sensation if the tooth pulp is vital. A relatively large current flows in the second circuit, and the magnitude of this current is determined by the voltage on the grid 26. The manner in which a test is performed will be described later.

A leak resistor 33, connected between the grid 55 and cathode of the left-hand section of tube 14, serves to drain off electrons from the grid 26, after the probe 31 has been removed from the tooth. The electron flow through this resistor produces a temporary negative bias on the grid 60 which checks electrons emitted from the cathode 24 and causes the plate current to return to zero.

It will be noted that the right-hand section of tube 14 is connected in shunt relation with the left-hand tube section and the associated meter 16. The right-hand tube section acts as a stabilizer for the left-hand tube section and insures that the plate current of the latter section will return to zero after each test. The right-hand tube section acts as a continuous 70 variable automatic load across the common D. C. supply for both tube sections.

The making of proper contact of the probe electrode 31 with the tooth under test is very important. The slightest variation of the con- 75

tact will affect the reading of the meter 16 and may give misleading information. To insure proper contact pressure between the probe electrode 31 and the tooth under test, the said electrode is carried by a slideable sleeve 35 which is urged outwardly of the casing 29 by a spring 36. When the sleeve 35 moves relative to the casing, the shielded wire 30 also moves. Furthermore, the probe device 28 is constructed and arranged to effect an increase in the voltage derived from potentiometer 10 whenever the pressure of electrode 31 on the tooth under test reaches a certain value as determined by the position of sleeve 35. To this end, there is provided on the probe device 28 an electrical switch comprising a pair of adjacent contact fingers 37 secured to casing 29 by screws 38 which also serve to secure a cover 39. The ends of contact fingers 37 project through an opening 41 in casing 29 into the path of a conductive member 42 on the end of sleeve 35. When the sleeve 35 moves to a certain position, the member 42 engages the ends of contact fingers 37 and thus interconnects them electrically. The switch comprising the two contact fingers is connected in circuit with the winding 43 of a relay 44 which may be supplied with energizing current from a low voltage source, e. g. the winding 20. The conductors 45 and 46 leading to the switch contact fingers are preferably provided with a grounded shield 47 which is only partially shown. The armature 48 of relay 44 controls a motor 49 whose shaft is mechanically connected through reducing gears 50 and a slip clutch 51 to the movable contact 25 of the potentiometer 10. The broken line representation indicates the mechanical connections of the said elements. The motor 49 may be energized from any suitable source, e. g. the supply lines leading to the primary of transformer 1.

In operation of the device, the switch 8 will usually be closed to provide pure D. C. voltage. Once the contacts 4, 5 and 11 have been adjusted to give the desired voltages, they need not be moved and are not manipulated during a test. 45 Prior to the making of a test, the contact 25 is manually adjusted to the zero voltage position, i. e. to the ground end of potentiometer 10. This is enabled by the slip clutch 51. The meter 16 reads zero.

With the electrode 27 and the probe 31 applied to the patient as above described, the operator exerts sufficient pressure on the tooth under test to cause closure of the switch on device 28, thereby causing operation of the motor 49. The motor drives contact 25 slowly, through reduction gears 50, in a direction to apply an increasing voltage to the electrode 27. When the patient experiences a mild sensation, the operator reads the meter 16 and immediately removes the probe 31. The operator then records the voltage and current readings which serve to indicate the condition of the tooth pulp at that time. Since the voltage reading is important, the potentiometer 10 should be provided with an indicating dial. The recorded readings may be compared with the results of earlier or later tests to determine whether the condition of the tooth pulp has become better or worse. The device enables making of successive tests under identical conditions.

If the sensation felt by the patient should be due to the passage of current through the tissue surrounding the tooth, rather than to the passage of current through the tooth pulp, the needle of meter 16 will fluctuate due to the fact that

tissue resistance varies slightly and the device is sufficiently sensitive to detect the voltage variations caused thereby. The fluctuation of the meter needle indicates at once to the operator that he is not getting a proper reading with respect to the tooth pulp.

Whenever the application of pure D. C. voltage fails to produce a sensation, the switch 8 may be opened to disconnect the filter condenser 7 and thus produce a ripple of the D. C. voltage. This will sometimes cause the tooth pulp to respond when it will not respond to pure D. C. voltage.

A device constructed according to the present invention has been used by an experienced dentist and has been found to be a great improvement over prior devices. The aforementioned advantages have actually been demonstrated.

While a particular embodiment of the invention has been illustrated and described, it will be apparent that the invention is not limited thereto. If desired, a recording microammeter may be employed to make a record on a card. In this way, successive records could be made on a single card of the condition of the pulp of a tooth at different times.

We claim:

1. In a tooth pulp tester, a double-triode vacuum tube, means for applying a positive potential to the anodes of said tube, current indicating means included in the anode circuit of one triode section of said tube, means connecting the other section of said tube in parallel relation with the first section and said indicating means, and means for applying a relatively low positive potential to the grid of the first section through the tooth pulp to be tested.

2. In a tooth pulp tester, a double-triode vacuum tube, means for applying a positive potential to the anodes of said tube, current indicating means included in the anode circuit of one triode section of said tube, means connecting the other section of said tube in parallel relation with the first section and said indicating means, a probe adapted to be applied to a patient's tooth to be tested, means connecting said probe to the grid of the first tube section, an electrode adapted to be applied to some part of the patient's body, and means for applying a relatively low positive potential to said electrode.

3. In a tooth pulp tester, a double-triode vacuum tube, means for applying a positive potential to the anodes of said tube, current indicating means included in the anode circuit of one triode section of said tube, means connecting the other section of said tube in parallel relation with the first section and said indicating means, a probe device including a probe adapted

to be applied to a patient's tooth to be tested, means connecting said probe to the grid of the first tube section, an electrode adapted to be applied to some part of the patient's body, means for applying a relatively low positive potential to said electrode, and means controllable from said probe device for varying said last-mentioned potential.

4. In a tooth pulp tester, a double-triode vacuum tube, means for applying a positive potential to the anodes of said tube, current indicating means included in the anode circuit of one triode section of said tube, means connecting the other section of said tube in parallel relation with the first section and said indicating means, a probe device including a movable probe adapted to be applied to a patient's tooth to be tested, means connecting said probe to the grid of the first tube section, an electrode adapted to be applied to some part of the patient's body, means for applying a relatively low positive potential to said electrode, switch means on said probe device operable by said movable probe according to the pressure applied to the tooth under test, and means controlled by said switch means for varying said last-mentioned potential.

5. In a tooth pulp tester, a double-triode vacuum tube, means for applying a positive potential to the anodes of said tube, current indicating means included in the anode circuit of one triode section of said tube, means connecting the other section of said tube in parallel relation with the first section and said indicating means, a probe device including a movable probe adapted to be applied to a patient's tooth to be tested, means connecting said probe to the grid of the first tube section, an electrode adapted to be applied to some part of the patient's body, means including a potentiometer for applying a relatively low positive potential to said electrode, means including a motor for actuating said potentiometer, and switch means on said probe device operable by said movable probe according to the pressure applied to the tooth under test and adapted to control said motor.
